(57) **CLAIM**

The ornamental design for a connector, as shown and described.

DESCRIPTION

FIG. 1 is a rear elevation view of a connector showing my design;

FIG. 2 is a top plan view thereof showing an image of a lock as a surface feature;

FIG. 3 is front elevation view thereof;

FIG. 4 is right side elevation view thereof;

FIG. 5 is a bottom elevation view thereof;

FIG. 6 is a left side elevation view thereof showing an image of a lock as a surface feature; and,

FIG. 7 is a perspective view thereof.

The broken line in the drawing views is included to show unclaimed environment only and forms no part of the claimed design.
